Albert M. Austin,
ATTORNEY

UNITED STATES PATENT OFFICE.

CHARLES N. COBYELL, OF MAMARONECK, NEW YORK.

VANITY CASE.

Application filed March 3, 1925. Serial No. 12,824.

The objects of this invention are to provide a case for carrying the usual mirror, puff, powder or other toilet accessories, which will be of particularly thin, flat form, 5 neat and attractive in appearance, simple and inexpensive in construction and consisting of but few parts, easily and inexpensively assembled.

One of the special novel features of the 10 invention is the formation of the casing from two duplicate cover sections, the both of which may be produced from the same die.

Another special novel feature is the holding 15 of the mirror or other toilet article in one of the cover sections by a ring or bezel formed to provide a container for a powder puff or the like and adapted also to act as a spring retainer for holding the cover sections in closed relation.

20 Additional novel features of the invention will appear as the specification proceeds.

In the drawings accompanying and forming part of this specification, one of the practical and preferred embodiments of the invention is illustrated, but the invention may be embodied in other structural forms as will be apparent from the broad scope of the following disclosure:

Figure 1 is a cross sectional view showing the case opened for use. Figure 2 is a plan view of one of the two cover sections. Figure 3 is an enlarged cross sectional view on substantially the line 3-3 of Figure 2, illustrating particularly one of the finger holds for opening the case. Figure 4 is an enlarged sectional view as on line 4-4 of Figure 2. Figure 5 is a broken plan view of the mirror holding ring. Figure 6 is an enlarged cross section of the same as on line 6-6 of Figure 5. Figure 7 is an edge view of the case in closed condition. Figure 8 is a plan view of the mirror holding ring as modified by the provision of lugs to hold a puff in position therein. Figure 9 is a cross sectional view of same as on line 9-9 of Figure 8. Figure 10 is a view similar to Figure 8 illustrating a further modification.

The two cover sections 5, 6, are shown as 50 of shallow, saucer-like form, each with an inturned bead or bezel 7 interrupted at one point 8 for the hinge and provided at a point to one side of the diametrical hinge line with a lug or finger hold 9. These duplicate case sections are connected by a suit-

able hinge, shown as made up of interfitting leaves 10, soldered or otherwise secured in the recesses 8 or to the ring or bezel 14 and connected by a pintle 11.

A mirror 12 is shown seated in the cover 60 section 6, held in place therein by the over-standing flanges 13 of a ring or bezel 14 having an annular wall 15 frictionally engaged with the inturned bead of this section. Between the foot of the annular wall and the flange which holds the mirror in place, the holding ring has a V-shaped annular indentation 16 which adds a certain amount of resiliency and provides a shoulder at 17 for positioning engagement with the edge of 70 the mirror. The bend 18 at the foot of the annular wall is usually made of slightly larger diameter than the rim of the bead so that the ring will snap into place within the bead and be yieldingly held in place by 75 the engagement of this shoulder behind the bead.

The mirror is held in place under the spring tension afforded by the flange 13 and the V-shaped bend 16 and this tension has 80 a further tendency to hold the annular shoulder 18 interlocked with the confining bead.

The annular wall of the mirror holding ring provides a receptacle for a powder 85 puff 19 or the like, and it is further utilized in the present instance as a catch for the other cover section by forming it at a point substantially opposite the hinge, with an outturned lug or spring tongue 20 adapted 90 to be engaged by the inturned bead on such cover section. As this holding tension is fairly light, the action of releasing the same does not disturb the interlocked engagement of the ring in the first cover section. 95

When the two cover sections are assembled, as in Figure 7, the opening lugs 9 which are off center with respect to the diametrical hinge line, Figure 2, will be positioned to opposite sides of the catch, conveniently accessible for releasing the catch. The positioning of these lugs to opposite sides of the center is an advantage in this thin case construction in that they are more exposed and hence more easily engaged than 105 if they were directly opposite.

A powder compact 21 or the like may be supported in the bottom cover section 5 as by engaging the backing 22 of the same beneath the bead of this cover section. 110

The making of the cover members as duplicate parts materially reduces the manufacturing costs because both covers can then be made from the one set of dies. This means also that the case is of exactly symmetrical form. The inturned flanges at the edges of the case sections reinforce the same, enabling said sections to be made of fairly light metal and these flanges abut when the case is closed, affording a firm joint and preventing distortion of the case by any unusual pressure.

The finger grips 9 for opening the case are shown formed integral with the case sections and produced by severing segmental portions of the flange 7 as on the lines 23, Figures 2 and 3, and then bending the same outward so that they project slightly beyond the rims of the case sections. As shown in the views referred to, these cuts do not extend inward the full width of the flanges 7 so that said flanges remain continuous and uninterrupted at these points.

As shown most clearly in Figure 3, these out-turned lips 9 are in effect outward extensions of the wall of the case sections projecting therefrom substantially at the juncture of the wall with the rim flange 7. These projections are so slight as not to mar the otherwise smooth thin appearance of the case, as shown in Figure 7.

If desired, the holding ring 14 may be provided with one or more lugs 24, turned inward at the edge of the upright or annular wall 15 to serve as a catch or catches for retaining the powder puff, as indicated in Figure 9.

Figure 8 shows how more than one of these lugs may be provided at relatively widely separated points, and Figure 10 shows how a single extended lug or flange may be employed. Without these lugs, the puff will ordinarily be retained within the ring by its close fitting engagement therein, as indicated in Figure 1, but the lugs insure that on opening the case, the puff will be retained in the upper cover, in position to be conveniently removed for use.

What is claimed is:—

50. 1. A vanity case comprising hingedly connected duplicate cover sections having annular inturned flanges at the edges of the same meeting in the closed relation of the covers an annular continuous holding ring sprung past the flange in one cover section and having a portion projecting for co-operation with the flange of the other cover section to form a catch, said ring having an inwardly extending flange overlying the bottom of the cover section in which it is seated and a toilet article held by said flange against the bottom of said cover section.

60. 2. A vanity case comprising hingedly connected duplicate cover sections having inturned flanges at the edges of the same meet-

ing in the closed relation of the covers, a holding ring sprung past the flange in one cover section and having a portion projecting for co-operation with the flange of the other cover section to form a catch, said ring 70 having an inwardly extending flange overlying the bottom of the cover section in which it is seated and a toilet article held by said flange against the bottom of said cover section and opening lugs on the cover sections, said lugs being disposed to opposite sides of a diametrical center line extending through the hinge and the spring catch being disposed substantially on said center line between the two offset lugs. 80

3. A vanity case comprising hingedly connected duplicate cover sections having inturned flanges at the edges of the same meeting in the closed relation of the covers, a holding ring sprung past the flange in one 85 cover section and having a portion projecting for co-operation with the flange of the other cover section to form a catch, said ring having an inwardly extending flange overlying the bottom of the cover section 90 in which it is seated and a toilet article held by said flange against the bottom of said cover section, said holding ring having an annular wall portion with a shoulder at the base of the same engaged beneath the 95 holding flange of the cover section and an annular bend between said shoulder and article holding flange.

4. A vanity case comprising duplicate cover sections hingedly connected together 100 and provided with abutting duplicate inturned annular flanges at the edges of the same, a mirror seated in one cover section, a holding ring sprung in engagement with the flange of said cover section and having a 105 portion overstanding the edge of the mirror and a spring catch portion on said ring releasably engaged by the flange of the other cover section.

5. A vanity case comprising shallow saucer-shaped covers of like construction, hingedly connected and having duplicate annular inturned flanges at the meeting edges of the same and an article holding member held by the inturned flange on one cover 115 and provided with a spring catch for engagement by the flange of the other cover.

6. A vanity case comprising shallow saucer-shaped covers of like construction, hingedly connected and having inturned 120 flanges at the meeting edges of the same and an article holding member held by the inturned flange on one cover and provided with a spring catch for engagement by the flange of the other cover, said member being 125 in the form of a ring having an annular wall held by the flange of the cover in which it is seated and projecting above the flange to form a compartment over the article held thereby. 130

7. A vanity case comprising shallow saucer-shaped covers of like construction, hingedly connected and having inturned flanges at the meeting edges of the same and an article holding member held by the inturned flange on one cover and provided with a spring catch for engagement by the flange of the other cover, said member being in the form of a ring having an 10 annular wall held by the flange of the cover in which it is seated and projecting above the flange to form a compartment over the article held thereby and a powder puff normally retained in said compartment.
8. A vanity case comprising shallow saucer-shaped covers of like construction, hingedly connected and having inturned flanges at the meeting edges of the same and an article holding member held by the 20 inturned flange on one cover and provided with a spring catch for engagement by the flange of the other cover, said member being in the form of a ring having an annular wall held by the flange of the cover in which it is seated and projecting above the flange to form a compartment over the article held thereby and a powder puff normally retained in said compartment, said annular wall having an inturned lug at the outer edge of the same for retaining engagement over said puff.
9. A vanity case comprising hingedly connected cover sections, an article seated in one of said cover sections, a retaining ring engaged in said cover section over said article and having a projecting annular wall forming a compartment and a powder puff normally held in and retained by said compartment.
10. A vanity case comprising hingedly connected cover sections, an article seated in one of said cover sections, a retaining ring engaged in said cover section over said article and having a projecting annular wall forming a compartment and a powder puff normally retained in said compartment, said wall having an inturned lug at the outer edge of the same for retaining engagement over said puff.
11. A vanity case comprising hingedly connected cover sections having inturned flanges at the meeting edges of the same, said flanges having portions thereof severed therefrom and bent outward to provide projecting finger grips for opening the case. 50
12. A vanity case having a cover section provided with an inturned annular flange having a portion severed therefrom and bent outward to provide a projecting grip for operating said cover section. 60
13. A vanity case comprising duplicate saucer shaped covers, a hinge connecting said covers, each cover having a finger hold at its meeting edge and on one side of the diametrical line extending through the hinge, 65 and catch means for holding said covers in closed position.
14. A vanity case comprising covers, a hinge connecting said covers, each cover having a finger hold; said finger holds being spaced in the direction of the meeting edges of the covers, and catch means for holding said covers in closed position. 70
15. A vanity case comprising saucer shaped covers, each cover having a convex 75 bottom surrounded by an annular inturned, inwardly rolled flange, hinge means connecting said covers, said flanges being disposed in close relation when said case is closed to provide a thin edge.
16. A vanity case comprising saucer shaped covers, each cover having a convex bottom surrounded by an annular inturned flange, said flanges being disposed in close relation when the case is closed to provide 80 a thin edge, hinge means connecting said covers, an article holding member retained by the inturned flange of one cover and provided with a spring catch for engagement with the other cover. 85

In testimony whereof I have hereunto set my hand.

CHARLES N. CORYELL.
